UNITED STATES PATENT OFFICE

2,490,610

STOWAGE LIFT

Nils Peter Erik Andersen, Elm Grove, Wis., assignor to Harnischfeger Corporation, Milwaukee, Wis., a corporation of Wisconsin

Application September 19, 1946, Serial No. 697,973

3 Claims. (Cl. 212—134)

1

This invention relates to stevedoring tackle intended for use between decks of a ship as an aid in stowing and breaking out package cargo, and it resides more specifically in a novel form of the same including a base-guided, self-elevating high-lift hook joined by hoisting lines with a portable trolley adapted to engage the lower flanges of overhead deck beams to provide an overhead anchorage from which hoisting force may be applied to the hook at any point throughout the hold.

In handling cargo between decks heavy packages are usually moved to and from the hatches and stowed positions by skidding them on the deck. Every effort is made to avoid the necessity of raising such heavy packages for stowage in upper courses of cargo because of the difficulty of locating skids upon which such packages may be warped to the level desired. As a result, cargo space is often left unused unless sufficient light packages suitable for stowage on upper levels are available. No apparatus sufficiently portable and universal in its function to permit a heavy lift to be made at any point desired throughout the hold has heretofore been available. Through the instant invention, however, means are provided by which a heavy lift, carried close to the maximum height of the hold, can be made at any point throughout the hold by comparatively simple and easily performed rigging operations.

This invention is herein described by reference to the accompanying drawings forming a part hereof and in which there is set forth by way of illustration and not of limitation one form in which the apparatus of this invention may be embodied.

In the drawings:

Fig. 1 is a side view in elevation of one form of the apparatus of this invention shown in position within a fragment of a ship's hold, the latter being shown in section;

Fig. 2 is a front view in elevation of the apparatus shown in Fig. 1;

Fig. 3 is an enlarged detail view in transverse section of the apparatus shown in Fig. 1 viewed through the plane 3—3 there indicated;

Fig. 4 is an enlarged detail fragmentary side view in elevation with parts broken away and in section of the apparatus shown in Fig. 1; and

Figure 5 is an enlarged perspective view of the trolley.

As shown in the drawings the apparatus of this invention is adapted for use within the hold of a ship 1 having a plurality of decks 2 and 3 the latter being of conventional construction re-

2

inforced by steel channel or angle deck beams 4. As a general practice the deck beams 4 are ordinarily positioned parallel to one another athwartship with a uniform spacing throughout the vessel. Depending upon this habit of construction the apparatus of this invention is provided with an overhead anchorage trolley 6 comprising a frame 7, transverse axles 8, outwardly facing wheels 9, inwardly facing wheels 41 and a head block 10. Secured to the frame of the trolley 6 is a pair of horizontally acting retaining rollers 11 so positioned as to cooperate with wheels 41 and to positively retain the trolley 6 upon the lower flanges of an adjacent pair of deck beams 4.

The trolley 6 is preferably made of the lightest possible construction consistent with strength, using for the purpose lightweight alloys and the like with the object in view of confining the weight of the same within limits which can be conveniently handled manually. To permit shifting of the trolley 6 from one pair of deck beams 4 to another the axles 8 are provided with detachable sleeves 12 which may be manually separated or locked in place as desired, thus permitting the trolley to be removed manually from one pair of deck beams 4 and placed upon any other desired. Head block 10 is carried on a swivel mounting not shown borne upon a sub-carriage 13 having rollers 14 thus permitting the head block 10 to turn or to be shifted longitudinally of the axle to accommodate to the position of the load.

Arranged to be joined with the block 10 by means of a hoisting line 15 is a high-lift base-supported hook assembly 16 made up of a base 17 having a fulcrum support 42, a boom 18 of length greater than the spacing between decks and a hook end 19. Mounted upon the boom 18 are guide sheaves 20 and 21 arranged to lead the hoisting line 15 to a fair engagement with sheave 22 of a longitudinally movable double block 23 carried on the lower part of the boom 18 as shown. The longitudinally movable double block 23 is made up of a trunnion shaft 24 carrying end rollers 25 and having a transverse threaded hole adapted to engage an actuating screw 26 mounted upon boom 18 as shown in Fig. 4. The double block 23 also includes in addition to the sheave 22 previously referred to, a similar sheave 27 mounted as shown more clearly in Fig. 3. End rollers 25 are positioned between and guided by inwardly facing guide rails 5 secured

to the inner faces of the channels making up the boom 18.

Hoisting line 15 after passing around sheave 22 extends to and passes around a sheave 28 mounted near the upper end of the boom 18 and then returns to the sheave 27, and after passing around the same extends to a dead end connection 29 secured to the upper end of the boom 18.

The screw 26 previously mentioned is mounted for rotation in an upper bearing 30 and extends downwardly through a lower bearing 31 to join with a beveled driving pinion 32 secured to its lower end. The pinion 32 is arranged to be driven by gear 33 mounted upon the output shaft of a power unit 34 carried upon the base 17. The base 17 is also provided with a power supply cable reel 35 from which a flexible power cable 36 extends to be joined with suitable power outlets situated in convenient locations throughout the ship. Extending upwardly from the base 17 in the fashion of a hand truck handle is a handle bar 31 permitting the hook 16 to be manually shifted, an operation which is facilitated by the balancing effect of the power unit 34 with respect to the boom 18.

In operation with the trolley 6 in place for the performance of a lift, the hook end 19 of the assembly 16 is manually brought to a position approximately below the trolley 6. The power unit 34 is then operated by manipulation of control 38 so as to move the double block 23 upwardly on the boom 18 making available slack in the hoisting line 15. The end 39 of the line 15 is then removed from its anchorage on the boom 18 and manually reeved through the head block 10 and brought back to its anchorage and secured. The apparatus is now in condition to perform a lift which is accomplished by manipulating the control 38 so as to cause the double block 23 to be moved downwardly on the boom 18 thus raising the boom 18 to a position, for example, as indicated by broken lines in Fig. 1. Thereupon slings may be adjusted to a package 40 as shown and thereafter by further operation of the power unit 34 the package 40 may be brought to the position shown in Fig. 1. It will be understood, of course, that horizontal movement of the package 40 throughout the length of the beams 4 may be manually effected in conjunction with the lift just described and in this way cargo may be stowed or broken out from upper courses even though of substantial bulk and weight.

By reason of the ready portability of the overhead anchorage trolley 6, arrangements may be quickly made for the lifting of loads at any point throughout the hold. When not in use the base supported hook assembly may be readily moved out of the way and stowed. The mechanism further is simple and obvious in its manner of functioning and may readily be operated by skilled stevedores without special instruction or experience. By reason of the nature and construction of the base supported high-lift hook utilization of the head room of the hold to a degree exceeding that of the usual hoisting means is made possible.

A further aspect of utility of the apparatus of this invention is the availability of the hoisting line 15 for use as a whip line or skid line for dragging packages across the deck. When it is desired that the line 15 be used in this manner the parts are raised to the position shown in Fig. 1 and the hook 16 secured to the trolley 6 by a temporary connection not shown. This permits

the end 39 of line 15 to be removed from its anchorage at the end of boom 18 and upon manipulation of the control 38 to be fed out over sheave 21 for use as a whip or skid line. In case of such use the trolley 6 is preferably locked against horizontal movement by means not shown so as to provide sufficient reaction to permit the sliding of a heavy package across the deck.

I claim:

1. In a cargo stowing tackle adapted for use between decks of a cargo vessel the combination comprising an overhead anchorage means adapted to engage and be secured to overhead deck beams of a deck of said cargo vessel; a base supported high-lift hook assembly having a hook end adapted to be raised and lowered, a base end adapted for fulcrumed support on a deck beneath said first mentioned deck, and a boom portion of length substantially greater than the spacing between said decks, joining said base end and hook end; and power operated hoisting means mounted on said high-lift hook assembly adapted to engage said overhead anchorage means and the hook end of said base supported hook and to move said hook end to and from said anchorage means.

2. In a cargo stowing tackle the combination comprising a shiftable overhead anchorage means adapted to engage and derive support from overhead deck beams of a deck of a cargo vessel, a base supported high-lift hook assembly having a hook end adapted to be raised and lowered, a base end adapted for fulcrumed support on a deck beneath said first mentioned deck, and a boom portion of length substantially greater than the spacing between decks joining said base end and hook end; and power operated hoisting means adapted to engage said overhead anchorage means and the hook end of said base supported hook and to move said hook end to and from said anchorage means.

3. In a cargo stowing tackle the combination including an overhead anchorage means comprising a trolley adapted to engage and derive support from the lower flanges of overhead deck beams of a cargo vessel, said trolley including a head block; a base supported high-lift hook assembly having a hook end adapted to be raised and lowered, a base end adapted for fulcrumed support on a deck beneath said first mentioned deck, and a boom portion of length substantially greater than the spacing between decks, joining said base end and hook end; a hoisting line extending from said hook end of said high-lift hook assembly to said head block on said trolley and back to said boom; and power operated means mounted on said high-lift hook assembly adapted to extend and retract said hoisting line to cause raising and lowering of said hook end.

60 NILS PETER ERIK ANDERSEN.
